HEEL-ATTACHING MACHINE

William Roderick Barclay and Frank Barton,
Leicester, England, assignors to United Shoe
Machinery Corporation, Paterson, N. J., a
corporation of New Jersey

Application July 25, 1934, Serial No. 736,882
In Great Britain November 18, 1933

16 Claims. (Cl. 1—32)

This invention relates to the attaching of heels by machine to shoes, and is particularly, but by no means exclusively, concerned with the attaching of wood heels to women's shoes by fasteners, 5 usually nails, driven from inside the shoe.

In attaching wood or other high heels to women's shoes, it is usually desirable to hold the heel on the shoe by members which contact not only with the tread of the heel but with its side 10 and rear surfaces, owing to it being difficult to apply sufficient heel-clamping pressure to the tread alone without incurring great liability of breaking the heel.

It is an object of the present invention to provide for the secure holding of high heels which 15 can not be subjected to great pressure applied to their tread surfaces without liability of breakage. In the attainment of this object there is employed, in a heel-attaching machine, a heel-abutment arranged to apply only a predetermined and limited pressure to one part, usually 20 the tread, of a heel, this application being under the control of another abutment or abutments, as those engaging the sides of the heel, which may apply such greater pressure as may be required to hold the heel firmly for attaching.

There is disclosed herein means for maintaining the clamping pressure substantially perpendicular to the tread-surface of the heel. This is 30 not broadly a part of the present invention, being the subject of Letters Patent of the United States No. 2,050,312, Grewcock, Aug. 11, 1936.

The above and other features of the invention will become apparent from a consideration of the 35 following description, given by way of example and with reference to the accompanying drawings of a convenient construction according to the invention, in which drawings,

Fig. 1 is a side view of the upper part of a heel-attaching machine fitted with heel-holding mechanism according to the invention;

Fig. 2 is a front view of some parts of Fig. 1; and

Fig. 3 is a side view, partly in section and on 45 a larger scale, of a portion of Fig. 2.

The invention may be embodied in any usual form of heel-attaching machine in which there is relative movement between a heel-abutment and a shoe-entering jack or similar member, for 50 instance a machine as shown in Letters Patent of the United States No. 1,926,147, Gouldbourn et al, September 12, 1933. A heel-abutment head or housing 12 is arranged for movement along a vertical path to clamp a heel, being mounted 55 at the bottom of a plunger 14 which slides in a

vertical bore in an overhanging part of a heel-attaching machine frame 10. In the head 12 is mounted a stem 16 which operates a tread-face-engaging device or abutment 18, this stem 16 engaging the forward end of a compensating lever 20, the rear end of which acts upon an abutment 22 for the rear surface of the heel. The rear abutment 22 is normally biased upwardly by a light spring 23, pushing the tread-abutment stem 16 downward. Engaging the lever 20, and forming a movable pivotal point therefor, are two transverse levers 24 (Fig. 2) which operate heel side abutments 26.

In the present construction, the tread-face-engaging abutment 18 is carried upon a block 30 mounted upon a pair of arms 32 which are pivoted at their inner ends to the machine column 10. The abutment 18 is angularly adjustable on the block 30 by a hand-worm 33 which meshes with a worm-segment formed on said abutment. 20 The block is fixed in different positions along the arms 32 by screws 35 which pass through slots in the arms so that the distance of the abutment from the column, and therefore from the back of a shoe located on a shoe-entering member or jack 40 (Fig. 1), may be adjusted. 25 The arms are arranged for pivotal connection to any one of an upwardly and outwardly inclined series of openings 36, 37, 38 (Fig. 1) in a block 30 fixed to the column 10. The upper face of the block 30 contacts with a partly spherical knob or contact member 42 on the under side of an adjustable inner stem-piece 43 threaded into the stem 16. The knob 42 has a flat under side relatively to which the block 30 slides when the main abutment-head 12 descends to clamp a heel. 35

The pivot-point of the arms 32 is adjusted upwardly or downwardly to one or another of the openings 36, 37, 38, according to the height of the heel being attached, in such a manner that the block 30 presents the abutment 18, when the head 12 is moved down, with its under side substantially parallel to the tread-face of the heel. The abutment actually moves to heel-clamping 40 position along an arcuate path the radius of which is represented by the arms 32. The final movement along this path is substantially perpendicular to the heel-tread-face. The block 30 is maintained normally raised by a tension-spring 44, the connection for which will be later described, so that it always remains in contact 45 with the knob 42. There have been described two separate adjustments which alter the position of the block 30 and the abutment 18. First, move- 50

ment of the block 30 along the arms 32 by the worm 33 alters the effective length of the arms and the radius of the path of the block, and, second, application of the pivot of the arms to one or another of the openings 36, 37, 38 changes the position of the center of the path. The upper pivotal opening 36 will be employed when extra-high heels (more than 3½ inches, say) are to be attached to shoes. As shown, the center opening 37 may be employed for heels up to that height, although the upper point may be used for heels of any greater height than three inches. The lower opening 38 will be used for heels of less than two inches in height, it being generally desirable to locate the lower surface of the block 30, when down, as close to parallelism with the tread-face of the heel as possible, avoiding excessive angular adjustment between the block and the abutment 18, that shown in Figs. 1 and 3 being an approximate maximum. The inner stem-piece 43 may be adjusted vertically relatively to the housing 12 by a hand-wheel 45 (Fig. 1) which is connected by a rod 47 (Fig. 3) to the stem 16. Rotation of the stem 16 by the wheel 45 causes the member 43, which is kept from rotating by a guide 49, to be screwed either in or out of the stem 16. The abutment 22 is self-adjustable with reference to the rear surface of a heel, it being movable in a circular guideway in its holder 25. This holder is horizontally adjustable by a hand-screw 29 relatively to its carrying stem 31, which is engaged by the rear end of the lever 20. By its adjustments, the block 30 may be set to seat the abutment 18 accurately upon and to move substantially perpendicularly to tread-surfaces of heels of widely varying height and pitch, such accurate seating being specially desirable when the heels are highest.

To limit the pressure which is to be applied to a specified part of a heel, the forward ends of the arms 32 are connected by a cross-piece 46 to a rod 48 which extends vertically to a slide-plate 50 mounted within a fixed guideway 52 formed upon the front face of the overhanging part of the machine-frame 16 in which the abutment-plunger 14 is guided. The plate 50 is pulled upwardly by the spring 44, above mentioned, and has ratchet-teeth on its opposite sides engaged by two pairs of pawls 54, 56 pivoted upon the guideway 52. The levers 24 which operate the side abutment members 26 have fixed to them upwardly extending arms 60 (Fig. 1) connected by a spring 62, which tends to hold the members 26 raised and apart from one another. The levers 24 also carry at the forward ends of their pivots upstanding fingers 64, having horizontal extensions which are adapted to engage tail-pieces of the pawls 54, 56 in such a manner that when the abutment members 26 receive their first movement towards a heel, the fingers 64 are moved laterally away from the pawls and release them. Therefore, one or another of the pawls engages, under the pull of tension-springs 66, 68, a tooth on the ratchet on one side or the other of the plate 50. The teeth on one side of the plate are cut so as to lie vertically between the teeth on the other side, to give a locking action at half the distance between the teeth on either side. Also of the pairs of pawls on either side of the plate 50, one pawl is farther above its pivot by the distance of one quarter of a tooth than the other. Thus, locking can be insured at quarter-tooth distance. When a pawl engages the plate 50, the arms 32 and the tread-abutment 18 carried by them become locked against down-

ward movement, and further descent of the abutment-housing 12, either by action of the machine-operator through a treadle, or under power of the machine applied automatically before the nails are driven to fasten a heel to a shoe, results solely in further depression of the rear and side abutments. The amount of pressure that will be applied to the tread-surface of a heel by mechanism arranged as just described may be determined and regulated by adjusting the pull of the spring 62 which tends to hold the side abutment members 26 apart. This adjustment may be effected by joining the spring to one of the arms 60 by an eye-bolt 70, which may be varied as to its projection through the arm by turning the nut. 15

When a heel is clamped by moving towards it the abutment-housing 12 containing members operating as above described, the abutment 18 will first engage the tread of the heel. As soon as this has occurred, further movement of the housing 12 causes the compensating lever 20 to rock, its front end moving upwardly relatively to the housing, and the rear abutment 22 to move down into contact with the rear of the heel. Any further rocking movement of the lever 20 is then prevented by the seating of the rear member 22 on the heel, and downward movement of the housing 12 continues while the lever 20 remains at rest. Consequently, the side abutment members 26 are moved in against the heel because the inner ends 30 of their levers 24 are within the lever 20. At this time, the tread-abutment 18 becomes locked by the engagement of a pawl 54 or 56 with the ratchet-plate 50, and further downward movement of the housing increases only the pressure 35 applied to the heel by the rear and side abutments. The pawls 54 and 56 are forced by the fingers 64 out of engagement with the ratchet-plate, when the side abutments return with the housing to their original positions after a heel has 40 been attached.

It will be understood that a device acting to limit the pressure applied to a part of a heel by a tread or other abutment may be, according to the invention, applied to an organization in which 45 such abutment moves along a common path with abutments arranged to apply pressure to other parts of a heel.

Having described the invention, what we claim as new and desire to secure by Letters Patent of 50 the United States is:

1. In a heel-attaching machine, a plurality of pressure-abutments movable into engagement with a heel, and means controlled by one abutment while it is in motion for limiting the pressure applied by another abutment. 55

2. In a heel-attaching machine, a plurality of pressure-abutments movable into engagement with a heel, and means made effective upon the movement of one abutment for positively locking 60 another abutment against movement.

3. In a heel-attaching machine, a plurality of pressure-abutments movable into engagement with a heel, means made effective upon the movement of one abutment for positively locking another abutment against movement, and means arranged to vary the resistance to movement of the abutment effecting the locking action. 65

4. In a heel-attaching machine, a plurality of pressure-abutments movable into engagement 70 with a heel, and a member movable as a result of the engagement to limit the pressure applied by one of the abutments.

5. In a heel-attaching machine, a plurality of pressure-abutments movable into engagement 75

with a heel, a locking member for one of the abutments, and means for normally holding the member out of locking engagement, said holding means being released upon movement toward the heel of an abutment other than that to be locked.

5. In a heel-attaching machine, a plurality of pressure-abutments movable into engagement with a heel, a locking member for one of the abutments, means for normally holding the member out of locking engagement, said holding means being released by movement toward the heel of an abutment other than that to be locked, means for resisting such movement, and means arranged to vary the resistance.

10. In a heel-attaching machine, a pressure-abutment, movable means for supporting the abutment, and a locking member movable into engagement with the supporting means and arranged to resist the advance of the abutment to 20 apply pressure to the work.

15. In a heel-attaching machine, a jack for receiving a shoe and a heel to be attached, a pressure-head co-operating with the jack, a pressure-abutment movable upon the head, a second pressure-abutment movable upon the head as a result of engagement of the first abutment with a heel upon the jack, and a locking member for 25 the first abutment made effective upon movement of the second abutment toward the heel.

20. In a heel-attaching machine, a jack for receiving a shoe and a heel to be attached, a pressure-head co-operating with the jack, a pressure-abutment movable upon the head, a second pressure-abutment movable upon the head as a result of engagement of the first abutment with a heel upon the jack, a spring resisting movement of the second abutment, and a locking member for the first abutment made effective upon movement of the second abutment toward the 40 heel.

25. In a heel-attaching machine, a jack for receiving a shoe and a heel to be attached, a pressure-head co-operating with the jack, a pressure-abutment movable upon the head, a second pressure-abutment movable upon the head as a result of engagement of the first abutment with a heel upon the jack, a spring resisting movement of the second abutment, a locking member for the first abutment made effective upon movement of the second abutment toward the heel, and means arranged to vary the resistance of the spring.

30. In a heel-attaching machine, a jack for receiving a shoe and a heel to be attached, a pressure-head co-operating with the jack, a pressure-abutment and side abutments movable

upon the head, and means made effective upon movement of the side abutments toward a heel for limiting the pressure applied by the tread-abutment.

35. In a heel-attaching machine, a jack for receiving a shoe and a heel to be attached, a pressure-head cooperating with the jack, a tread-abutment, a rear abutment and side abutments movable upon the head, means for moving the side abutments into engagement with a heel after engagement of the tread and rear abutments therewith, and a locking member for the tread-abutment controlled by the side abutments.

40. In a heel-attaching machine, a jack for receiving a shoe and a heel to be attached, a pressure-head cooperating with the jack, a tread-abutment, a rear abutment and side abutments movable upon the head, means for moving the side abutments into engagement with a heel after engagement of the tread and rear abutments therewith, a normally ineffective locking member for the tread-abutment, and means controlled by the side abutments for releasing the locking member.

45. In a heel-attaching machine, a jack for receiving a shoe and a heel to be attached, a pressure-head cooperating with the jack, a tread-abutment, a rear abutment and side abutments movable upon the head, means for moving the side abutments into engagement with a heel after engagement of the tread and rear abutments therewith, a locking member for the tread-abutment controlled by the side abutments, a spring acting to separate the side abutments, 30 and means arranged to vary the force of the spring.

50. In a heel-attaching machine, a frame, a pressure-head movable thereon, a tread-abutment movable by the head, an arm pivoted upon the frame and supporting the tread-abutment, a toothed slide movable upon the frame with the tread-abutment, and a pawl carried by the frame and engaging the slide-teeth.

55. In a heel-attaching machine, a frame, a pressure-head movable thereon, a tread-abutment and side abutments movable by the head, an arm pivoted upon the frame and supporting the tread-abutment, a toothed slide movable upon the frame with the tread-abutment, a pawl 50 carried by the frame and engaging the slide-teeth, and a member movable with the side abutments for contact with the pawl.

WILLIAM RODERICK BARCLAY. 55
FRANK BARTON.
